ELLIS F. FROST, OF WASHINGTON, DISTRICT OF COLUMBIA.

ELECTRIC ACTION FOR ORGANS.

1,228,899.

Specification of Letters Patent.

Patented June 5, 1917.

Application filed June 5, 1914. Serial No. 343,305.

To all whom it may concern:

Be it known that I, ELLIS F. FROST, a citizen of the United States, and resident of Washington, District of Columbia, have invented certain new and useful Improvements in Electric Actions for Organs, of which the following is a full, clear, and exact specification.

This invention relates to electric actions for organs and has for its object the production of a novel, useful, and feasible arrangement and control of the various means employed.

In the drawing forming a part hereof Figure 1 is a representation in diagram of the mechanisms employed together with the circuits and the relation of the same.

Fig. 2 is a section on the line 2—2 of Fig. 1.

Fig. 3 is an end view of the switchbar A¹⁴ and a front view of carrier A²¹.

Figs. 2 and 3 show the relation of the contact *h* of carrier A²¹ and its adjacent projecting contact *f* of switchbar A¹⁴. The relation of the other carrier contacts to their respectively adjacent projecting switchbar contacts is similar to that shown in Figs. 2 and 3.

Fig. 4 is a side view of a key and its associated contacts.

Fig. 5 is a view in perspective of a portion of a carrier, as A¹⁶, viewed from underneath and from the contact spring side of the carrier, or as seen from the top side of the drawing and from beneath. Thus viewed, the order of the contacts is the reverse of that shown in Fig. 1, so that whereas in Fig. 1 the order from left to right is *g*, *h*, in Fig. 5 it is *h*, *g*, from left to right. In Fig. 5 the number of contact springs requisite to the octave, as from *c* to *c'* inclusive, are shown, *g*, *g'*, *g''*, *g'''*, *g''''*, and *h* respectively corresponding to *c*, *c#*, *e*, *a#*, *b*, and *c'* of the scale.

In the drawing, D represents a battery A⁴⁶, B⁴⁶, A⁴⁷, B⁴⁷, A⁴⁸, and B⁴⁸, each represents a note sounding device of the usual electro-magnetic construction for the control of the speaking of an organ pipe associated therewith, said pipe not being shown in the drawing. Each of the note sounding devices A⁴⁶, A⁴⁷, A⁴⁸, is designed to control the speaking of a different organ pipe of a register, while the note sounding devices B⁴⁶, B⁴⁷, B⁴⁸, are each designed to control the speaking of a different organ pipe of another

register. A⁴⁶, A⁴⁷, A⁴⁸, may represent any three note sounding devices controlling the organ pipes of a register, while B⁴⁶, B⁴⁷, B⁴⁸, represent the corresponding note sounding devices controlling the organ pipes of another register. It is desirable to consider A⁴⁶, A⁴⁷, and A⁴⁸, as representing note-sounding devices controlling organ pipes serially an octave apart. And so with regard to the note sounding devices B⁴⁶, B⁴⁷, and B⁴⁸.

A¹⁶ to A²¹ inclusive and B¹⁶ to B²¹ inclusive represent carriers of insulating material each independently movable longitudinally and each designed to carry contacts represented by *g*, *h*, and *i*.

A¹³, A¹⁴, A¹⁵, and B¹³, B¹⁴, B¹⁵, represent switchbars of conducting material. Switchbars A¹³, A¹⁴, and A¹⁵, are placed adjacent to and at right angles to the contact carriers A¹⁶ to A²¹ inclusive. Switchbars B¹³, B¹⁴, and B¹⁵, are placed adjacent to and at right angles to carriers B¹⁶ to B²¹ inclusive. Switchbar A¹³ is placed adjacent to the *g* contacts of carriers A¹⁶ to A²¹ inclusive. Switchbar A¹⁴ is placed adjacent to the *h* contacts of carriers A¹⁶ to A²¹ inclusive. Switch-bar A¹⁵ is placed adjacent to the *i* contacts of carriers A¹⁶ to A²¹ inclusive. Switch-bar B¹³ is placed adjacent to the *g* contacts of carriers B¹⁶ to B²¹ inclusive. Switch-bar B¹⁴ is placed adjacent to the *h* contacts of carriers B¹⁶ to B²¹ inclusive. Switch-bar B¹⁵ is placed adjacent to the *i* contacts of carriers B¹⁶ to B²¹ inclusive.

Each switch-bar is movable in relation to the adjacent contacts. The relation of each switch-bar to its adjacent contacts is such that when a contact and its adjacent switch-bar are in the unoperated position they are out of engagement and can only be brought into engagement upon their being conjointly in the operated position. It is the function of the several carriers to bring their contacts into the range of movement of the switch-bars adjacent to those contacts.

For the purpose of facilitating the drawing of the claims and for the sake of simplifying the description of this invention each switch-bar and its adjacent contacts are considered as constituting a multiple circuit closer since by these instrumentalities any one of several circuits may be closed by the movement of the switch-bar and the proper carrier to their operative positions, each multiple circuit closer therefore including independently movable contacts and a switch-

bar, each contact and the adjacent switch-bar constituting a complete circuit closer within the meaning of certain of the appended claims. Thus the *g* contacts of carriers 5 A^{16} to A^{21} inclusive and the adjacent switch-bar A^{13} constitute multiple circuit closer No. 1: the *h* contacts of carriers A^{16} to A^{21} inclusive and the adjacent switch-bar A^{14} constitute multiple circuit closer No. 2: the *i* contacts of carriers A^{16} to A^{21} inclusive and the adjacent switch-bar A^{15} constitute multiple circuit closer No. 3: the *g* contacts of carriers B^{16} to B^{21} inclusive and the adjacent switch-bar B^{13} constitute multiple circuit closer No. 4: the *h* contacts of carriers B^{16} to B^{21} inclusive and the adjacent switch-bar B^{14} constitute multiple circuit closer No. 5: and the *i* contacts of carriers B^{16} to B^{21} inclusive and the adjacent switch-bar B^{15} constitute multiple circuit closer No. 6.

In the drawing each switch-bar is represented as carried by an insulating support and as having projections *a* to *f* each to engage with an adjacent contact. The projections *a*, *b*, *c*, *d*, *e*, *f*, of switchbar A^{13} are designed to engage respectively with the *g* contact springs of carriers A^{16} , A^{17} , A^{18} , A^{19} , A^{20} , A^{21} ; the projections *a*, *b*, *c*, *d*, *e*, *f*, of switchbar A^{14} are designed to engage respectively with the *h* contact springs of carriers A^{16} , A^{17} , A^{18} , A^{19} , A^{20} , A^{21} ; the projections *a*, *b*, *c*, *d*, *e*, *f*, of switchbar A^{15} are designed to engage respectively with the *i* contact springs of carriers A^{16} , A^{17} , A^{18} , A^{19} , A^{20} , A^{21} ; the projections *a*, *b*, *c*, *d*, *e*, *f*, of switchbar B^{13} are designed to engage respectively with the *g* contact springs of carriers B^{16} , B^{17} , B^{18} , B^{19} , B^{20} , B^{21} ; the projections *a*, *b*, *c*, *d*, *e*, *f*, of switchbar B^{14} are designed to engage respectively with the *h* contact springs of carriers B^{16} , B^{17} , B^{18} , B^{19} , B^{20} , B^{21} ; and the projections *a*, *b*, *c*, *d*, *e*, *f*, of switchbar B^{15} are designed to engage respectively with the *i* contact springs of carriers B^{16} , B^{17} , B^{18} , B^{19} , B^{20} , B^{21} .

Each circuit closer may be controlled by stops and a key, a stop for the control of each carrier and the key for the control of the switch bar. Wherefore it is clear that 50 each stop controls the movement of a contact of each of several multiple circuit closers whereas each key controls the switch-bar of but one multiple circuit closer.

If desired, each carrier may be controlled 55 by an electro-magnet and each switch-bar may also be controlled by an electro-magnet, the first mentioned electro-magnets each to be controlled by a stop and the second mentioned electro-magnets each to be controlled 60 by a key.

In the drawing, A^{22} to A^{27} inclusive and B^{22} to B^{27} inclusive represent electro-magnets each respectively controlling carriers 65 A^{16} to A^{21} inclusive and B^{16} to B^{21} inclusive. A^{10} , A^{11} , A^{12} , and B^{10} , B^{11} , B^{12} , represent

electro-magnets each respectively controlling switch-bars A^{13} , A^{14} , A^{15} , and B^{13} , B^{14} , B^{15} .

Electro-magnets A^{22} to A^{27} inclusive are controlled each respectively by stops A^{40} to A^{45} inclusive, and electro-magnets B^{22} to B^{27} inclusive are controlled each respectively by stops B^{40} to B^{45} inclusive.

Electro-magnets A^{10} , A^{11} , A^{12} , are each respectively controlled by keys A^1 , A^2 , and A^3 and electro-magnets B^{10} , B^{11} , B^{12} , are each respectively controlled by keys B^1 , B^2 , B^3 . 75

Electro-magnets A^{22} to A^{27} inclusive, B^{22} to B^{27} inclusive are connected in parallel to one pole of the battery D.

Electro-magnets A^{22} to A^{27} inclusive are each respectively connected to stop controlled contacts A^{28} to A^{33} inclusive adjacent to each of which respectively are the stop controlled contacts A^{34} to A^{39} inclusive which are connected to the other pole of the battery D. Each pair of these contacts is kept out of engagement when the controlling stop is "in" and is allowed to engage when the controlling stop is "out." 90

Electro-magnets B^{22} to B^{27} inclusive are likewise each respectively connected to stop controlled contacts.

Electro-magnets A^{10} , A^{11} , A^{12} , and B^{10} , B^{11} , B^{12} , are connected in parallel to one pole of the battery D. 95

Electro-magnets A^{19} , A^{11} , A^{12} , are each respectively connected to key controlled contacts A^5 , A^7 , A^9 , and their respectively adjacent contacts A^4 , A^6 , A^8 , are connected to the other pole of the battery D. Each pair of these contacts is kept out of engagement except when their respective controlling keys A^1 , A^2 , A^3 , are depressed. 100

Electro-magnets B^{10} , B^{11} , B^{12} , are each respectively connected to key controlled contacts B^5 , B^7 , B^9 , and their respectively adjacent contacts B^4 , B^6 , B^8 , are connected to the same pole of the battery D as are the contacts A^4 , A^6 , A^8 . Each pair of these contacts is kept out of engagement except when their respective controlling keys B^1 , B^2 , B^3 , are depressed. 110

The contacts *g* of multiple circuit closer No. 1 are connected as follows: Contact *g* of carrier A^{16} is connected to note sounding device A^{46} ; contact *g* of carrier A^{17} is connected to note sounding device B^{46} ; contact *g* of carrier A^{18} is connected to note sounding device A^{47} ; contact *g* of carrier A^{19} is connected to note sounding device B^{47} . 115

The contacts *h* of multiple circuit closer No. 2 are connected as follows: Contact *h* of carrier A^{16} is connected to note sounding device A^{47} ; contact *h* of carrier A^{17} is connected to note sounding device B^{47} ; contact *h* of carrier A^{18} is connected to note sounding device A^{48} ; contact *h* of carrier A^{19} is connected to note sounding device B^{48} ; con- 125

130

tact *h* of carrier A^{20} is connected to note sounding device A^{46} ; and contact *h* of carrier A^{21} is connected to note sounding device B^{46} .

- 5 The contacts *i* of multiple circuit closer No. 3 are connected as follows: Contact *i* of carrier A^{16} is connected to note sounding device A^{48} ; contact *i* of carrier A^{17} is connected to note sounding device B^{48} ; contact *i* of carrier A^{20} is connected to note sounding device A^{47} ; and contact *i* of carrier A^{21} is connected to note sounding device B^{47} .

10 The contacts *g* of multiple circuit closer No. 4 are connected as follows: Contact *g* of carrier B^{16} is connected to note sounding device A^{46} ; contact *g* of carrier B^{17} is connected to note sounding device B^{46} ; contact *g* of carrier B^{18} is connected to note sounding device A^{47} ; and contact *g* of carrier B^{19} is connected to note sounding device B^{47} .

15 The contacts *h* of multiple circuit closer No. 5 are connected as follows: Contact *h* of carrier B^{16} is connected to note sounding device A^{47} ; contact *h* of carrier B^{17} is connected to note sounding device B^{47} ; contact *h* of carrier B^{18} is connected to note sounding device A^{48} ; contact *h* of carrier B^{19} is connected to note sounding device B^{48} ; contact *h* of carrier B^{20} is connected to note sounding device A^{46} ; and contact *h* of carrier B^{21} is connected to note sounding device B^{46} .

20 The contacts *i* of multiple circuit closer No. 6 are connected as follows: Contact *i* of carrier B^{16} is connected to note sounding device A^{48} ; contact *i* of carrier B^{17} is connected to note sounding device B^{48} ; contact *i* of carrier B^{20} is connected to note sounding device A^{47} ; and contact *i* of carrier B^{21} is connected to note sounding device B^{47} .

25 Thus each contact of a multiple circuit closer is connected to a different note sounding device.

30 Thus each note sounding device is connected to a contact of each of several multiple circuit closers; as note sounding device A^{46} is connected to carrier A^{16} *g* contact of multiple circuit closer No. 1, to the carrier A^{20} *h* contact of multiple circuit closer No. 2, to the carrier B^{16} *g* contact of multiple circuit closer No. 4, to the carrier B^{20} *h* contact of multiple circuit closer No. 5; as the note sounding device B^{46} is connected to the carrier A^{17} *g* contact of multiple circuit closer No. 1, to the carrier A^{21} *h* contact of multiple circuit closer No. 2, to the carrier B^{17} *g* contact of multiple circuit closer No. 4, to the carrier B^{21} *h* contact of multiple circuit closer No. 5; as the note sounding device A^{47} is connected to the carrier A^{16} *h* contact of multiple circuit closer No. 2, to the carrier A^{18} *g* contact of multiple circuit closer No. 1, to the carrier A^{20} *i* contact of multiple circuit closer No. 3, to the carrier B^{16} *h* contact of multiple circuit closer

35 closer No. 5, to the carrier B^{18} *g* contact of multiple circuit closer No. 4, to the carrier B^{20} *i* contact of multiple circuit closer No. 6; as the note sounding device B^{47} is connected to the carrier A^{17} *h* contact of multiple circuit closer No. 2, to the carrier A^{19} *g* contact of multiple circuit closer No. 1, to the carrier A^{21} *i* contact of multiple circuit closer No. 3, to the carrier B^{17} *h* contact of multiple circuit closer No. 5, to the carrier B^{19} *g* contact of multiple circuit closer No. 4, to the carrier B^{21} *i* contact of multiple circuit closer No. 6; as the note sounding device A^{48} is connected to the carrier A^{16} *i* contact of multiple circuit closer No. 3, to the carrier A^{18} *h* contact of multiple circuit closer No. 2, to the carrier B^{16} *i* contact of multiple circuit closer No. 6, to the carrier B^{18} *h* contact of multiple circuit closer No. 5; and as the note sounding device B^{48} is connected to the carrier A^{17} *i* contact of multiple circuit closer No. 3, to the carrier A^{19} *h* contact of multiple circuit closer No. 2, to the carrier B^{17} *i* contact of multiple circuit closer No. 6, to the carrier B^{19} *h* contact of multiple circuit closer No. 5.

40 The note sounding devices, A^{46} , A^{47} , A^{48} , and B^{46} , B^{47} , B^{48} , are connected in parallel to one pole of the battery D.

45 The switch-bars A^{13} , A^{14} , A^{15} , and B^{13} , B^{14} , B^{15} , are connected to the other pole of the battery D.

50 The various moving parts except the stops are moved against restoring springs, (not shown).

55 The operation of this invention is as follows:

60 When no keys are depressed and no stops are in the "out" position, nothing is operated and no note is sounded by the note sounding devices.

65 If key A^1 be depressed a circuit is closed through the electro-magnet A^{10} and the switch-bar A^{13} of multiple circuit closer No. 1 is moved to operative position. Similarly 110 the operation of keys A^2 , A^3 , B^1 , B^2 , B^3 , closes circuits through electro-magnets A^{11} , A^{12} , B^{10} , B^{11} , B^{12} , and moves the switch-bars A^{14} , A^{15} , B^{13} , B^{14} , B^{15} of multiple circuit closers 2, 3, 4, 5, 6, to operative position. 115

70 No note sounding device is brought into action by these operations.

75 If stop A^{40} alone be drawn to the "out" position a circuit is closed through electro-magnet A^{22} and carrier A^{16} is moved so as 120 to bring its contacts *g*, *h*, *i*, respectively into the range of movement of switch-bars A^{13} , A^{14} , and A^{15} . If, now, while stop A^{40} is drawn switch-bar A^{13} be moved by depressing key A^1 a circuit is closed through the note sounding device A^{46} by reason of the engagement of the contact *g* of the operated carrier A^{16} by the operated switch-bar A^{13} ; if switch A^{14} be moved by depressing key A^2 a circuit is closed through the note sounding device A^{47} ; if switch A^{15} be moved by depressing key A^3 a circuit is closed through the note sounding device A^{48} .

ing device A⁴⁷ by reason of the engagement of the contact *h* of the operated carrier A¹⁶ by the operated switch-bar A¹⁴; if switch A¹⁵ be moved by depressing key A³ a circuit is closed through the note sounding device A⁴⁸ by reason of the engagement of the contact *i* of the operated carrier A¹⁶ by the operated switch-bar A¹⁵.

If stop A⁴¹ alone be drawn to the "out" position a circuit is closed through the electro-magnet A²³ and carrier A¹⁷ is moved so as to bring its contacts *g*, *h*, *i*, respectively into the range of movement of switch-bars A¹³, A¹⁴, and A¹⁵. If, now, while stop A⁴¹ is drawn switch-bar A¹³ be moved by depressing key A¹ a circuit is closed through the note sounding device B⁴⁶ by reason of the engagement of the contact *g* of the operated carrier A¹⁷ by the operated switch-bar A¹³; if switch-bar A¹⁴ be moved by depressing key A² a circuit is closed through the note sounding device B⁴⁷ by reason of the engagement of the contact *h* of the operated carrier A¹⁷ by the operated switch-bar A¹⁴; if switch-bar A¹⁵ be moved by depressing key A³ a circuit is closed through the note sounding device B⁴⁸ by reason of the engagement of the contact *i* of the operated carrier A¹⁷ by the operated switch-bar A¹⁵.

If stop A⁴² alone be drawn to the "out" position a circuit is closed through the electro-magnet A²⁴ and carrier A¹⁸ is moved so as to bring its contacts *g*, *h*, *i*, into the range of movement of switch-bars A¹³, A¹⁴, and A¹⁵. If, now, while stop A⁴² is drawn switch-bar A¹³ be moved by depressing key A¹ a circuit is closed through the note sounding device A⁴⁷ by reason of the engagement of the contact *g* of the operated carrier A¹⁸ by the operated switch-bar A¹³; if switch A¹⁴ be moved by depressing key A² a circuit is closed through the note sounding device A⁴⁸ by reason of the engagement of the contact *h* of the operated carrier A¹⁸ by the operated switch-bar A¹⁴.

If stop A⁴³ alone be drawn to the "out" position a circuit is closed through the electro-magnet A²⁵ and carrier A¹⁹ is moved so as to bring its contacts *g*, *h*, *i*, into the range of movement of switch-bars A¹³, A¹⁴, and A¹⁵. If, now, while stop A⁴³ is drawn switch-bar A¹³ be moved by depressing key A¹ a circuit is closed through the note sounding device B⁴⁷ by reason of the engagement of the contact *g* of the operated carrier A¹⁹ by the operated switch-bar A¹³; if switch A¹⁴ be moved by depressing key A² a circuit is closed through the note sounding device B⁴⁸ by reason of the engagement of the contact *h* of the operated carrier A¹⁹ by the operated switch-bar A¹⁴.

If stop A⁴⁴ alone be drawn to the "out" position a circuit is closed through the electro-magnet A²⁶ and carrier A²⁰ is moved

so as to bring its contacts *g*, *h*, *i*, into the range of movement of switch-bars A¹³, A¹⁴, and A¹⁵. If, now, while stop A⁴⁴ is drawn switch-bar A¹⁴ be moved by depressing key A² a circuit is closed through the note sounding device A⁴⁶ by reason of the engagement of the contact *h* of the operated carrier A²⁰ by the operated switch-bar A¹⁴; if switch-bar A¹⁵ be moved by depressing key A³ a circuit is closed through the note sounding device A⁴⁷ by reason of the engagement of the contact *i* of the operated carrier A²⁰ by the operated switch-bar A¹⁵.

If stop A⁴⁵ alone be drawn to the "out" position a circuit is closed through the electro-magnet A²⁷ and carrier A²¹ is moved so as to bring its contacts *g*, *h*, *i*, into the range of movement of switch-bars A¹³, A¹⁴, and A¹⁵. If, now, while stop A⁴⁵ is drawn switch-bar A¹⁴ be moved by depressing key A² a circuit is closed through the note sounding device B⁴⁶ by reason of the engagement of the contact *h* of the operated carrier A²¹ by the operated switch-bar A¹⁴; if switch-bar A¹⁵ be moved by depressing key A³ a circuit is closed through the note sounding device B⁴⁷ by reason of the engagement of the contact *i* of the operated carrier A²¹ by the operated switch-bar A¹⁵.

If the stops and keys be operated collectively in any combination the above described results are in no way changed.

What has above been described with reference to the operation of the A stops and A keys is equally applicable to the operation of the B stops and B keys in which case the B carriers and B switch-bars are involved instead of the A carriers and A switches.

The circuits involved can be readily traced by one skilled in the art.

If keys A¹, A², A³, be considered as belonging to one keyboard and B¹, B², B³, as belonging to another keyboard it follows that a given note sounding device can be operated by a key in either keyboard either of the same pitch, or of the octave below, or of the octave above, singly or simultaneously.

It is obvious that further duplications of keyboards requires but a like duplication of the arrangement shown and described.

It is obvious that equivalent electro-magnetic apparatus, as solenoids, may be substituted for the electro-magnets.

Having described my invention, I claim:

1. An electric organ-action comprising a source of electrical energy, note sounding devices, and circuit closers each including independently movable contacts and a switch-bar, each contact of a circuit closer connected to a different note sounding device, each note sounding device connected to a contact of each of several circuit closers, said note sounding devices connected in parallel to

- one pole of the source of electrical energy, and said switchbar connected to the other pole of the source of electrical energy.
2. An electric organ comprising a source of electrical energy, note sounding devices, circuit-closers each including independently movable contacts and a switchbar, each contact of a circuit closer connected to a different note sounding device, each note sounding device connected to a contact of each of several circuit closers, said note sounding devices connected in parallel to one pole of the source of electrical energy, said switchbars connected to the other pole of the source of electrical energy, electro-magnetic devices controlling a circuit closer, keys and drawstops and drawstop circuits and key circuits each including one of said electro-magnetic devices.
- 10 3. An electric organ-action comprising note sounding circuits, note sounding devices, circuit closers each including independently movable contacts and a switchbar, devices operating the contacts and other devices operating the switchbars, each circuit including a note sounding device and also the switchbar and a contact of each of several circuit closers.
4. An electric organ - action comprising note sounding circuits, note sounding devices, circuit closers each including independently movable contacts and a switchbar, devices operating the contacts and other devices operating the switchbars, each of the contact operating devices being common to a contact of each of several circuit closers, each circuit including a note sounding device and also the switchbar and a contact of each of several circuit closers.
- 15 5. An electric organ comprising note sounding circuits, note sounding devices, circuit closers each including independently movable contacts and a switchbar, devices operating the contacts and other devices operating the switchbars, each of the contact operating devices being common to a contact of each of several circuit closers, each circuit including a note sounding device and also the switchbar and a contact of each of several circuit closers, keys and drawstops, key circuits each including a switchbar operating device, and drawstop circuits each including a contact operating device.
- 20 6. An electric organ comprising a source of electrical energy, note sounding devices, circuit closers each including independently movable contacts and a switchbar, each contact of a circuit closer connected to a different note sounding device, each note sounding device connected to a contact of each of several circuit closers, said note sounding devices connected in parallel to one pole of the source of electrical energy, said switchbars connected to the other pole of the source of electrical energy, electro-magnetic contact operating device of each of said circuit closers.
- 25 7. An electric organ-action comprising a source of electrical energy, note sounding devices, circuit closers, keys, and drawstops, each circuit closer including independently movable drawstop controlled contacts and a key controlled switchbar, each contact of a circuit closer connected to a different note sounding device, each note sounding device connected to a contact of each of several circuit closers, said note sounding devices connected in parallel to one pole of the source of electrical energy, and said switchbars connected to the other pole of the source of electrical energy.
- 30 8. An electric organ comprising a source of electrical energy, note sounding devices, circuit closers, and electro-magnetic operating devices therefor, each circuit closer including independently movable electro-magnetically operated contacts and an electro-magnetically operated switchbar, each contact of a circuit closer connected to a different note sounding device, each note sounding device connected to a contact of each of several circuit closers, said note sounding devices connected in parallel to one pole of the source of electrical energy, and said switchbars connected to the other pole of the source of electrical energy, keys and drawstops and drawstop circuits and key circuits each including one of the electro-magnetic operating devices of a circuit closer.
- 35 9. An electric organ-action comprising a source of electrical energy, note sounding devices, circuit closers each including independently movable contacts and a switchbar, each contact of a circuit closer connected to a different note sounding device, each note sounding device connected to a contact of each of several circuit closers, said note sounding devices connected in parallel to one pole of the source of electrical energy, and said switchbars connected to the other pole of the source of electrical energy, a separate electro-magnetic means operating each of the several contacts of a circuit closer, said operating means each including an electro-magnet and a controlling drawstop therefor, and an operating means for each switchbar said means including an electro-magnet and a controlling key therefor.
- 40 10. An electric organ-action comprising a source of electrical energy, note sounding devices, and circuit closers each including relatively movable contacts and a switch

- bar, each contact of a circuit closer connected to a different note sounding device, each note sounding device connected to a contact of each of several circuit closers, said note sounding devices connected in parallel to one pole of the source of electrical energy, said switchbars connected to the other pole of the source of electrical energy, electro-magnetic means and circuits therefor and drawstops controlling said circuits for simultaneously moving a contact of each of several circuit closers into the range of movement of the adjacent switchbars. 55
11. An electric organ-action comprising a source of electrical energy, note sounding devices, and circuit closers each including relatively movable contacts and a switchbar, each contact of a circuit closer connected to a different note sounding device, each note sounding device connected to a contact of each of several circuit closers, said sounding devices connected in parallel to one pole of the source of electrical energy, said switchbars connected to the other pole of the source of electrical energy, and electro-magnetic means for simultaneously moving a contact 60 of each of several circuit closers into the range of movement of the adjacent switchbars. 65
12. An electric organ-action comprising a source of electrical energy, note sounding devices, and circuit closers each including relatively movable contacts and a switchbar, each contact of a circuit closer connected to a different note sounding device, each note sounding device connected to a contact of each of several circuit closers, said note sounding devices connected in parallel to one pole of the source of electrical energy, said switchbars connected to the other pole of the source of electrical energy, and electro-magnetic means and circuits therefor and drawstops controlling said circuits for simultaneously moving a contact of each of several circuit closers into the range of movement of the adjacent switchbars. 70
13. An electric organ-action comprising a source of electrical energy, note sounding devices, and circuit closers each including relatively movable contacts and a switchbar, each contact of a circuit closer connected to a different note sounding device, each note sounding device connected to a contact of each of several circuit closers, said note sounding devices connected in parallel to one pole of the source of electrical energy, said switchbars connected to the other pole of the source of electrical energy, and electro-magnetic means and circuits therefor and drawstops controlling said circuits for simultaneously moving a contact of each of several circuit closers into the range of movement of the adjacent switchbars. 75
14. An electric organ-action comprising a source of electrical energy, note sounding devices, and circuit closers each including independently movable contacts and a movable switchbar the movement of said switchbar and a contact being necessary to effect their engagement, each contact of a circuit closer connected to a different note sounding device, each sounding device connected to a contact of each of several circuit closers, said note sounding devices connected in parallel to one pole of the source of electrical energy, and said switchbars connected to the other pole of the source of electrical energy. 80
15. An electric organ comprising note sounding devices, multiple-contact circuit closers, keys, and drawstops, each contact of a circuit closer connected to a different note sounding device, each note sounding device connected to a contact of each of several circuit closers, said keys operating said note sounding devices subject to the control of said drawstops. 85
16. An electric organ comprising note sounding devices, multiple contact circuit closers, keys, and drawstops, each contact of a circuit closer connected to a different note sounding device, each note sounding device connected to a contact of each of several circuit closers, said keys operating said note sounding devices in unison, suboctave, and superoctave pitch relation to said keys subject to the control of said drawstops. 90
- ELLIS F. FROST.
